UNITED STATES PATENT OFFICE.

MATHIAS ANTES, OF NEW YORK, N. Y., ASSIGNOR TO MARGARETHA
ANTES, OF NEW YORK, N. Y.

NON-REFILLABLE BOTTLE.

No. 814,008.

Specification of Letters Patent.

Patented March 6, 1906.

Application filed October 10, 1905. Serial No. 282,080.

To all whom it may concern:

Be it known that I, MATHIAS ANTES, a subject of the German Emperor, residing at New York, in the county of New York and State 5 of New York, have invented certain new and useful Improvements in Non-Refillable Bottles, of which the following is a specification.

The present invention pertains to improvements in bottles, and has for its object 10 to arrange the bottles so as to render them non-refillable.

Contrary to the hitherto-known non-refillable bottles, my construction is of great 15 simplicity and of small expense in comparison with ordinary bottles.

To make my invention clear, I have illustrated the same in the accompanying drawings, in which similar reference-letters denote corresponding parts, and in which—

20 Figure 1 is an elevational view of my improved bottle, the upper part thereof being shown in vertical section with the ball-valve therein closed. Fig. 2 is a similar vertical section of the upper part of the bottle, showing the ball-valve raised and in open position, the lower part of the bottle being broken away. Fig. 3 is a cross-section through line 25 xx of Fig. 1 as viewed in the direction of the arrow y in Fig. 1, and Fig. 4 is the same section as viewed in the direction of the arrow z of Fig. 1.

With reference to the drawings, a denotes the bottle, which has a short hollow neck b . The inner surface of the neck b has at its 35 lower end an inwardly-projecting rib c , the upper surface of which is spherically shaped to form a seat for a glass ball d , serving to close the bottle when the latter is once filled. Cast onto or otherwise applied to the upper 40 end of the neck b is a cylindrical glass case e , the upper end f of which is formed to a neck to receive an ordinary stopper g . The inner surface of the cylindrical case e is ribbed upon its entire circumference, the ribs i thereof extending from the upper edge of the neck b 45 upward and terminating below the neck f . The size of the case e in diameter is somewhat larger than that of the ball d , and the ribs i project so far inward that between the outer edges thereof a free cylindrical space is 50 formed the diameter of which is equal to that of the glass ball. The latter will thus

be allowed to enter the said cylindrical space and to lie therein in close contact with the ribs.

Over the upper edges of the ribs i within the case is arranged a stationary circular disk j , which covers the cylindrical space i and has openings k all around its circumference adapted to register with the free spaces 60 formed between the individual ribs i .

The vertical extension of the cylindrical space i from the upper edge of the neck b up to the circular disk j is so large as to allow the ball-valve d to enter the space almost entirely 65 when the bottle is tilted or turned upside down.

In order to fill the bottle with the desired liquid, the glass ball must be raised from its seat and held in its raised position until the 70 filling is completed. For this purpose I have provided the glass ball d with a narrow bore b . The latter must be as short as possible, so as not to form a channel through which the liquid could be injected into the bottle. 75 I prefer, therefore, to form a curved segmental bore, as shown by the dotted lines in Figs. 1 and 2, whereby the ends of the bore b are brought together as close as possible to each other. The said bore serves as a passage for 80 a piece of wire, cord, or the like, m , by means of which the ball may be raised and held in its raised position. Before the glass case e is fixed to the neck b of the bottle the ball d , with the wire or cord passed through its bore 85 b , is inserted into the cylindrical space between the vertical ribs i of the case e . The ends of the wire or cord may be passed through either of the openings k in the plate j and the neck f outward, and by pulling them the glass 90 ball is raised. After the bottle has been filled the wire or cord is extracted, whereupon the glass ball drops onto its seat c . The neck f of the case e is then closed by an ordinary stopper g .

To prevent any instrument from being inserted through the neck and opening of the plate to raise the glass ball d , so as to be able to refill the bottle, the inner surface of the neck f is made flaring, as shown in Fig. 1, and 100 the inner diameter at the bottom of the neck is made equal to or slightly smaller than that of the solid central part of the disk j . If an attempt should be made to insert an instru-

100

ment through the neck, the same would meet the solid part of the disk *j*, which would obstruct the way to the glass ball.

All the parts of the device rendering the bottle non-refillable are preferably made of glass. The disk *j* may be cast integrally with the case *e*.

What I claim, and desire to secure by Letters Patent, is—

- 10 1. A non-refillable bottle having a neck provided with a spherically-shaped seat for a ball-valve, a case fixed to said neck, the inner surface of said case being provided with ribs extending vertically upward, and forming 15 between their inner edges a free cylindrical space the diameter of which is equal to that of the glass ball, to allow the latter to enter said space and to fit closely therein, a circular disk closing up the top of said free space and 20 having openings all around its circumference, said openings registering with the spaces between the individual ribs, and a neck at the upper end of the case to receive a stopper, substantially and for the purpose as specified.

2. A non-refillable bottle having a neck 25 provided with a spherically-shaped seat for a ball-valve, a case fixed to the said neck, the inner surface of the said case being provided with ribs extending vertically upward and forming between their inner edges a free cylindrical space the diameter of which is equal to that of the ball-valve, a circular disk closing up the top of said free space and having 30 openings registering with the spaces between the individual ribs, a neck at the upper end of the case to receive a stopper, the opening in the neck of the case being at its bottom smaller in diameter than the central part of the disk covering the cylindrical space of the case between the inner edges of the ribs, substantially and for the purpose as specified. 35

In testimony whereof I affix my signature in presence of two witnesses.

MATHIAS ANTES.
